TAKE-UP MECHANISM

John Rinne, Brooklyn, N. Y., Everett H. Ashton, Belmar, N. J., and Robert G. Mallard, Staten Island, and Francis Gerard Lake, New York, N. Y., assignors, by mesne assignments, to Steel and Alloy Tank Company, Newark, N. J., a corporation of New Jersey

Original application April 2, 1947, Serial No. 739,004, now Patent No. 2,518,185, dated August 8, 1950. Divided and this application September 2, 1949, Serial No. 113,876

1 Claim. (Cl. 139—312)

1

The present invention relates to a cloth roll take-up mechanism for looms and is a division of application Serial No. 739,004, filed April 2, 1947, now Patent No. 2,518,185.

The continuous take-up motions heretofore used on automatic looms have the main part of their gear transmissions exposed, and in position to pick up dirt, lint, threads, waste or the like. These substances, besides interfering with proper power transmission to the take-up roll, so materially increase wear on the gears that frequent replacement of these gears is required. Also, since the gear transmission is exposed, lubrication thereof is a problem, and is often attended by a messy, oily condition around the loom.

The primary object of the present invention is to provide a take-up motion with a gear transmission effectively protected against exposure to dirt, lint, threads, waste or the like, effectively lubricated in a tidy manner, readily accessible, as for example, for pick adjustments, arranged to permit its easy mounting as a unit on the loom frame, and having each of its shaft elements rigidly supported.

Various other objects of the invention will be apparent from the following particular description, and from an inspection of the accompanying drawings, in which:

Fig. 1 is a front view of the left-hand side of a loom embodying the features of the present invention, certain parts of said loom not related to the present invention being absent from the view for the purpose of clarity;

Fig. 2 is a sectional view of the loom of Fig. 1 taken in a plane parallel to the plane of view of Fig. 1 and showing the internal arrangement of the gear box for the take-up mechanism;

Fig. 3 is a front view of part of the take-up gear box; and

Fig. 4 is a section of the take-up mechanism taken approximately along the lines 4—4 of Fig. 2.

Referring to the drawings, and especially to Fig. 1, the loom frame may be of the conventional type, but is desirably of the improved form shown in copending application, Serial No. 691,237, filed August 17, 1946, now Patent No. 2,533,128. In this improved type of loom, instead of the conventional loomsides, each with a single frame web, each loomsides comprises a pair of parallel webs 10 and 11 rigidly interconnected by suitable girts and bracing members.

Mounted near the front section of the loom is the take-up motion comprising a take-up roll 12 supported on the loomsides and covered with

sandpaper or similar rough surfaced material adapted to frictionally grip the cloth A after it is formed and advance it towards the cloth roll 13. The cloth roll 13 is pressed into contact with the take-up roll 12 and is frictionally driven thereby to wind the cloth around said roll 13.

The take-up roll 12 has secured to the ends thereof gudgeons 14 journalled in suitable bearings on the inside frame webs 10. The gudgeons 14 on the left-hand loomside has secured thereto between the two frame webs 10 and 11 a gear 16 by which the take-up roll 12 is continuously driven as the cloth is formed. The take-up roll gear 16 is driven from the crank shaft of the loom (not shown), which extends parallel to the axis of the take-up roll 12, and which drives through a pair of intermeshing gears (not shown) a short pick cam shaft (not shown), below said crank shaft on the left-hand side of the loom. On said pick cam shaft is connected a bevel gear (not shown) meshing with a second bevel gear (not shown) on a drive shaft 22 (Figs. 2 and 4). Between the drive shaft 22 and the take-up roll gear 16 is the take-up gear transmission.

As a feature of the present invention, the take-up gear transmission is mounted in a box or casting 25 formed with a peripheral wall 26, extending through an opening 27 in the outer frame web 11. The gear box 25 has a mounting flange 30 abutting the outer face of the frame web 11 around the web frame opening 27, and is closed at its left-hand side by a plate wall 28 secured to said flange 30 and to said frame web 11 by means of screw studs 31. The plate wall 28 is provided with a flanged opening 33 closed by a removable cover plate 34 supported in position by means of screw studs 35. The cover plate 34 is in readily accessible position and can be removed to permit access to the interior of the gear box 25, as for example, for the purpose of changing the speed ratio according to the desired pick. The cover plate 34 is desirably of transparent non-shattering material such as "Lucite" or "Plexiglass," to serve as a window, so that the interior of the gear box 25 can be easily observed.

The gear box 25 is provided with a partition wall 37 serving as a frame support for certain of the bearings of the shafts of the take-up transmission train, and has an outer wall 38 on its right-hand side, serving as a support for the bearings of some of the shafts of the gear train.

On the right-hand side of the gear box 25 is an extension 40 passing through an opening 41 in the inner frame web 10, and having a mount-

ing flange 42 by which said gear box extension is secured to the gear box wall 38 by means of screw studs 43. The drive shaft 22 passes through the rear wall of the gear box extension 40, is journalled in bearings 44 in said rear wall, and carries in the interior of said gear box extension a worm 45 meshing with a worm wheel 46 mounted on a take-up main drive shaft 47. The take-up main drive shaft 47 has one section journalled in bearings 48 in the box walls 37 and 38 respectively, and has a section of reduced diameter journalled in bearings 51 in the left-hand box wall 28 and passing through said latter wall to the outside of the gear box 25. The outer end of the reduced shaft section carries a hand wheel 52 for manually taking up or reversing the rotation of the take-up drive.

As a feature of the present invention, the take-up gear transmission between the take-up main drive shaft 47 and the take-up roll gear 16 is such as to permit quick and easy changes in speed ratios, in accordance with the picks per inch desired. To that end, the take-up gear transmission comprises a pinion 60 affixed to the take-up main drive shaft 47 between the two gear box plate walls 37 and 38, and meshing with a gear 61 on a first countershaft 62 journalled in spaced bearings 63 and 64 in said walls 37 and 38 respectively. Affixed to the overhanging section of the countershaft 62 is a first drive gear 65, which meshes with a first change gear idler 66 secured to an idler shaft 67 journalled in bearings in an idler gear adjusting bracket 68, and which is employed when operating in the lower pick range. The idler gear 66 meshes with a take-up driven change gear 69 on a second countershaft 70 supported in bearings 71 and 72 in the walls 37 and 38 respectively.

The bracket 68 is mounted for rotative idler gear adjusting movement about the axis of the countershaft 62, and comprises a pair of spaced plates 75 and 76 journalled on said countershaft 62, and rigidly held together by means of bolts 77 passing through respective spacer sleeves 78 between said plates. The bracket plates 75 and 76 carry respective bearings for the idler shaft 67 and respective hubs embracing the countershaft 62. Between the two bracket plates 75 and 76 is the first countershaft drive gear 65, and alongside of said gear is a second drive pinion 80 affixed to the countershaft 62. The drive pinion 80 is half the diametrical size of the first drive gear 65, and is employed when operating in the upper pick range. Meshing with the second drive pinion 80 is a second change gear idler 81 secured to a second idler shaft journalled in bearings in the bracket plates 75 and 76 respectively, and adapted to mesh with the take-up driven change gear 69 on the second countershaft 70, when said change gear is in position on said second countershaft reversed from that shown in Fig. 2 for operation in the upper pick range.

The bracket 68 may be rotated in adjusting position about the first countershaft 62, to bring either of the two idler gears 66 or 81 in mesh with the selected change gear on the second countershaft 70 according to the pick range desired, and is secured in adjusted position by means of a clamp secured to a boss on the gear box plate wall 37.

The driven gear 69 is mounted on a reduced section of the second countershaft 70, and in the lower pick range of operation, shown in Fig. 2, said pick change gear has an axial hub extension 87 abutting a shoulder on said countershaft at 76

the end of said reduced section. When the hub extension 87 extends to the right of the gear 69 as shown in Fig. 2, this pick change gear will be in mesh with the idler 66. The gear 69 is removably retained on the second countershaft 70 by means of a screw stud 80, and can be reversed in position on said second countershaft when it is desired to operate in the upper pick range.

Also affixed to the second countershaft 70 is a drive gear 92 mounted between the two walls 37 and 38, and meshing with a driven gear 93 on a third countershaft 94. The countershaft 94 is supported in bearings 95 and 96 in the walls 37 and 38 respectively, and extends to the outside of the gear box 25. On the projecting part of the countershaft 94 is affixed a drive gear 97 meshing with an idler gear 98 which is in mesh with the take-up roll gear 16, and is secured to an idler shaft 99 journalled in a bracket 100. The bracket 100 is supported for rotatable adjustment about the third countershaft 94 to maintain the idler gear 98 in mesh with the take-up roll gear 16.

As a feature of the present invention, means are provided for positively lubricating the gear transmission in the gear box 25, and for that purpose, the drive shaft 22 carrying the take-up worm 45 drives a lubricating oil pump 105 mounted in the gear box extension 40 on the front wall thereof. The lubricating pump 105 is shown of the gear type, and comprises a pair of meshing gears 106, serving as the pumping members, and one of which is fixed to the shaft 22 so as to be driven thereby. The pump 105 has an intake 107 leading from the sump section 107a of the gear box 25, and has an outlet 108 connected to a piping system 109 distributing oil to the different rotating members of the gear transmission. The oil distribution piping system 109 may be of any suitable type, and may have a manifold 110 at its upper end provided with openings for projecting the oil downwardly from the top of the transmission. The oil from the manifold 110 will find its way through the different rotating parts of the transmission and back into the sump 107a.

With the construction described, the box enclosed take-up gear transmission will be protected against lint, threads, waste and other foreign substances. Also, by means of this construction, each of the gears of the transmission is keyed to a shaft supported in two or more spaced bearings, so that a rigid inflexible structure free from vibration or play is afforded. Moreover, with this encased construction, lubrication of the gears and bearings is effected efficiently without creating an untidy, oily mess around the loom. Furthermore, the transmission structure being self-contained, it can be mounted or demounted with respect to the loom frame easily and quickly as a unit.

The transparent window 34 in the gear box 25 permits observation of the inside of said gear box, so that the condition of the lubricating system in operation can be observed. It is also possible to determine through the transparent window 34 the pick setting of the loom from the position of the pick change gear 69 and from the number of teeth thereon, which would be marked on the gear.

The construction of the present invention is provided with means for driving the take-up mechanism in the reverse direction to the extent required to effect the desired let-back whenever there is an absence of the filling, as a result, for example, of the breakage or exhaust of the running filling supply. To that end, or for the pur-

pose of manually pulling the cloth ahead or back, as is necessary in the initial starting of the loom or positioning the fell of cloth, there is a clutch 111 in the take-up transmission automatically disengaged upon detection of a failure in the filling. The clutch 111 is of the ratchet tooth type, and comprises a clutch element 112 fixed to the take-up worm wheel 46, and meshing with a complementary clutch element 113 feathered on the take-up main drive shaft 47 for slidable movement therealong.

The clutch element 113 is yieldably urged into drive engagement with the clutch element 112 by means of a coil spring 117 embracing the main shaft section 114, and bearing at one end against a shoulder or collar 118 on said shaft section, and at its other end against said clutch element 113.

The disengagement of the clutch 111 is effected automatically upon detection of a deficiency in filling by means of a filling feeler slide mechanism 119 which may be of the usual type, and which is operated when the filling breaks, or when the filling is being replenished, to move a rod 120 on the inner side of the inside frame web 10 downwardly. The rod 120 is guided for slid-able movement and urged upwardly in an inoperative position by means of a spring 121 seated on one of the slide sleeve guides 122 affixed to the inner face of the inside frame web 10, and bearing against a collar 123 secured to said slide rod 120. The slide rod 120 carries a block 124 which engages on its lower side, one end of a cam lever 125 pivoted to the front wall of the gear box extension 40, and which is adapted to engage on its upper side in the upper limiting position of said slide rod, a sleeve rod guide 129 affixed to the inner face of the inside frame web 10. The other end of the lever 125 has a cam conformation 127 engaging a cam follower 128 secured to a rock shaft 130 journaled in the front and rear walls of the gear box extension 40, and carrying inside said extension a fork 131 engaging the clutch element 113, and serving to shift said member out of engagement with the clutch element 112 when the slide rod 120 is depressed, either upon filling transfer action, the breakage of the filling, or for manual operation.

The slide rod 120 is automatically operated from the filling slide mechanism 119, or may be manually operated by means of a foot pedal 132 integral or otherwise secured to the collar 123.

Upon the automatic or manual disengagement of the clutch 111 in the manner described, the tension of the cloth A will cause a reverse drive or let-back of the transmission beyond said clutch 111 without interfering with the rotation of the drive shaft 22 and the intermeshing gear members 45 and 46 thereby.

As many changes can be made in the above apparatus, and many apparently widely different embodiments of this invention can be made without departing from the scope of the claim, it is intended that all matter contained in the above description or shown in the accompanying drawings shall be interpreted as illustrative and not in a limiting sense.

What is claimed is:

In a loom, a frame web extending along one side of said loom and having an opening, a take-up roll gear, a take-up main drive shaft, a gear transmission between said shaft and said gear, 20 a casing for said transmission passing through said web opening from the outer side thereof, and having an outer side wall mounted on said frame web, said outer side wall having an opening affording access to said transmission in the interior of said casing, and said casing comprising a removable cover plate for said last-mentioned opening on the outer side of said frame web.
